UNITED STATES PATENT OFFICE.

ERIC NEWHAM WATERWORTH, OF WEST HOBART, TASMANIA, AUSTRALIA.

STOPPING MEANS ADAPTED TO TALKING MACHINES.

Application filed August 23, 1926, Serial No. 131,045, and in Australia October 22, 1925.

This invention has reference to talking machines of the disc type and provides means for stopping a turntable on which is a record in a self acting way after the record has been played.

In already known stopping means, the tone arm of the machine has been used, during its movements across the record, to actuate the stopping levers. In the present 10 machine, while the moving tone arm is employed to control certain movements, its function so far as stopping the movement of the record is concerned, is limited to prevent the brake being applied until the movement of the tone arm ceases. This it does 15 by keeping separate in a positive way, except for a brushing contact at intervals, the brake operating parts while traversing the record, but when its movement ceases, then 20 parts, that hitherto have been kept in motion, have their rotary movements converted into a rocking movement, or rocking movements are induced, directly under the influence of the machine motor to free the brake 25 lever that is then applied to the turn table on which the record lies.

To this end, a pivotal member is intermittently moved into a position to engage the turntable brake actuating means, but before 30 the means has time to operate, is withheld by the moving tone arm until the movement of the tone arm ceases, when the pivotal member is engaged by the actuating means and the machine motor operates parts to release the brake.

There are various ways for effecting this operation an approved mode being one in which the machine motor is employed to actuate a wheel, called the pallet wheel, that at 40 intervals in its rotary movements engages a lever, called the pallet lever. The parts are so arranged that the rotary movement of the pallet wheel will be arrested by the pallet lever only when the tone arm and stylus 45 have come to the end of the record.

When this happens the power of the machine motor is applied to turn the pallet wheel and a plate upon which it is mounted, in an arc about the motor spindle axis. The 50 movement of the whole operates mechanism to release the brake to permit of its application to the turntable.

The tone arm connections are such that while the stylus is traversing the record arm 55 rest of the pallet wheel is rendered impossible. Its influence upon the pallet lever

during this period is to keep it away from the pallet wheel except for the brushing contact aforesaid. This is effected in a simple and direct way from the tone arm mounting by using a make and break pivot adapted to contact upon an extension from a pivoted Z shaped lever actuated from the tone arm mounting such pivot being upon an extension from the pivotally mounted pallet lever, 60 the make and break being governed from the rotary movement of the pallet wheel.

When the extension from the lever actuated from the tone arm mounting has been moved far enough due to the movement 70 across the record of the tone arm, say when the record has been about one third played, it will move a lever that bestrides the spindle mounting the pallet lever. The latter is kept in a backward position by a tension 75 spring secured to the bestriding lever and this spring must be relieved from duty in order to permit the arresting means to function. When the said extension contacts with the bestriding lever it will move it away 80 from the pallet lever against the tension spring and free the lever from its influence.

In the accompanying drawings,

Fig. 1 is a plan view of the machine, the turn table being shown in dotted lines and provided with a depending flange upon the inside surface of which the brake is applied.

Fig. 2 is a perspective view of part of the pallet wheel and pallet lever and a lever that disconnects at intervals the tone arm connections and the pallet lever, and

Fig. 3 is a like view of a lever and part of pallet lever by means of which the spring that tends to remove the pallet lever from the pallet wheel can be cut out of action.

At the base of the tone arm 4 an arm or bracket 5 is attached so as to move with the arm and on the bracket is a plate 6 having a curved edge concentric with the tone arm axis. On this plate is a pin or post 7 and adjacent thereto a lever 8 is pivotally mounted at 9. On the forward end of the lever is a jaw 10 and at the head of same a depending lug 11 is attached. In the drawing the tone arm is shown in position when the record is about one third played and the jaw 10 is about to be engaged by the post 7. The opening in the jaw provides for a fair amount of clearance between it and the post in order to allow for lash of same due to 100 swaying of the tone arm when the stylus is traversing an incorrectly centered record.

But when the tone arm is at the beginning of the record the post 7 will be some distance from the jaw and will steadily approach the same until the arm comes to the 5 position as in the drawing. During the approach the lever is locked by the plate 6 and lug 11 that rests against the curved plate until the position indicated is reached when the post enters the jaw.

10 On the other end of the lever 8 called the Z-shaped lever is a curved tail piece 12 the outer edge of which is a regular curve in an arc centering on 9 and its periphery may be smooth or knurled lightly with vertical 15 parallel regular grooves. The inner edge is also regular except towards its outer end where it is slightly reduced to provide a gradual incline from the tip inwards.

The motor is on the spindle 13 on which 20 is keyed the spur pinion 14 that meshes with the pallet wheel 15 on a spindle 16 mounted and supported in the plate 17 that pivots on the motor spindle 13. On the pallet wheel 15 is a post 18 and under the wheel 15 is 25 another pin 19 that is set slightly in advance of the post 18. The plate 17 is retained in position by the spring 20 against the post 20^a in the base plate 21. A rocking lever 22 is pivotally mounted in the base 30 plate at 23 and one end of this lever comes under the pallet wheel while its other part passes under the pallet lever 24 and is turned up closely adjacent to a flat spring 25 secured to pallet lever. On the end of this 35 spring is a knife edge 26 that contacts with the edge of the member 12.

The pallet lever 24 is shaped as a bell 40 crank and pivoted at 27 and on its pivotal axis is fitted a bestriding lever 28 that is extended under the pallet lever and turned up to bear against its edge as shown in Fig. 3: it is attached to a spring 29 secured to the bed plate. The back of this lever 28 bears against the inner edge of the member 45 12 that is inclined for the reason to be hereinafter explained.

On the other end of the pallet lever a rocking lever 30 is pivotally mounted and retained in position by a strong tension 50 spring 31 against an adjustable stop 31^a. This lever comes at one end over the pallet wheel 15 and is fitted with two members, one being a pallet formed with inclined plane surface 32 and the other a tooth 33 55 that is adapted to engage the pin 18 on the pallet wheel. This is for the purpose of arresting the movement of the pallet wheel when the progress of the tone arm ceases.

60 On the plate 17 is a pawl 34 that has an inclined surface in contact with a pin 35 on the base plate and which is adapted to neatly engage in the tooth on a quadrant 36 pivotally mounted at 37, the extension 65 from which is a lever 38 that terminates in

a setting handle 39 with an indicator over a calibrated plate 40. Pivotally mounted near to the quadrant at 41 is a rocking lever 42, held by the tension spring 44, the forward end of the lever being turned up to 70 engage in a nick in the quadrant 36 when the handle is set to the "on" position. Just next to the nick the quadrant edge slopes downwardly at 43 in order that, when the pawl engages the tooth in the quadrant it 75 will be drawn away from the lever 42 that will slide over the inclined edge 43 and be rocked by the spring to apply the brake 45 to the depending flange on the turn table 46.

In operation, the handle 39 is first moved 80 to the "on" position which sets the brake lever 42 upon the quadrant 36, pawl 34 being clear of the quadrant. The machine motor rotates the spur wheel 14 on the spindle 13 and the enmeshing pallet wheel 15. 85 As the wheel 15 rotates its pin 18 will, at each revolution, engage the inclining member 32 to rock the pallet lever against the spring 29 that afterwards reacts to return the lever. Meanwhile, the playing of the record has commenced and as the tone arm traverses the same and when it has advanced about one third across it, the post 7 engages in the jaw 10 of the pivoted Z-lever 8 which immediately commences to move. 90 This causes the advancement of the tail piece 12 the inclining end of which contacts with the bestriding lever 28 thus moving the turned up end of the lever away from the pallet lever and cutting out the influence of the spring 29. This freed position of the pallet lever 24 in relation to spring 29 is maintained until the playing of the record is finished and the tone arm is returned to its initial position. 100

The pallet lever is now free to move about its pivot and as the wheel 15 rotates and the pin 18 engages, it will continue at intervals to be drawn to the pallet wheel. Just prior to this movement the pin 19 will contact with the lever 22 to push same outwards to cause its other end to press against the spring 25 on which the knife edge 26 is mounted and to withdraw the part 26 from the edge member 12. This permits the pallet lever to be drawn in without putting strain on member 12, and through it and lever 8 to the delicate track of the record. Meanwhile, the part 12 is advancing and on the return of the knife edge to its former position it will engage the knurled edge of 12 that will move the pallet lever outwards from the pallet wheel. This rocking movement of the pallet lever 24 continues with each revolution of the pallet wheel until the playing of the record is finished and the tone arm has ceased to move. 115

At the next revolution of the pallet wheel the pin 18 engages the pallet lever member 32 as usual but owing to the member 12 be 120 130

ing stationary the lever will not be returned and on the next revolution of 15 the pin 18 will engage the tooth 33 thereby arresting the movement of the wheel 15 carried on the plate 17. When this occurs the plate 17 and wheel 15 are levered around the spindle 13 thus causing the pawl 34 to come into the tooth on the quadrant 36 and to move it far enough to disengage the brake lever 42 from the quadrant. The spring 44 then reacts to apply the brake 45 to the turntable and the lever handle 38 moves to the "off" position. When the plate 17 strikes the stop 47 the pressure of the pin 18, which is still under 10 the influence of the motor, and the momentum of the turntable causes the bell crank 30 to rock against the spring 31, when the pin 18 slips by the tooth and the plate 17 is returned by spring 20 to rest against the stop 20a.

Having now described my invention what I claim as new and desire to secure by Letters Patent is:—

1. In stopping means in talking machines, 25 a tone arm, a motor and brake releasing means, a pivotal member that is intermittently moved into a position to actuate means to release the brake and is withdrawn therefrom by the moving tone arm 30 until its movement ceases when the pivotal member is held and the motor induces movements to release the brake.

2. In stopping means in talking machines, 35 a tone arm, a motor and brake releasing means, a pallet wheel driven by the motor, a pallet lever that is engaged at intervals in brushing contact by the pallet wheel until the tone arm movement ceases when the pallet wheel becomes locked with the pallet 40 lever and the motor induces movements to release the brake.

3. In stopping means in talking machines, 45 a tone arm, a motor and brake releasing means, a pallet wheel driven by the motor, a plate pivotally mounted on the motor spindle on which plate the pallet wheel is mounted, a pallet lever engaged at intervals in brushing contact by the pallet wheel until the tone arm movement ceases when the pallet 50 lever, wheel and plate become locked, a pawl on the plate, a toothed quadrant that is engageable by the pawl and on which the braking means is held until the locked parts are rocked by the motor.

4. In stopping means in talking machines, 55 a pallet wheel rotated by a motor, a pallet lever that is kept separate from the pallet wheel (except for a brushing contact therewith at intervals) while a record is being played, a tone arm mounting, a pivoted lever and an extension thereon operated from said mounting and a make and break pivot flexibly mounted upon the pallet lever and adapted to contact with extensions on said 60 pivoted lever.

5. In stopping means in talking machines, 70 a pallet lever, a pallet wheel, a pin thereon, a tone arm mounting, a pivoted lever and an extension thereon operated from said mounting, a make and break pivot flexibly mounted upon the pallet lever adapted to contact with extension on said lever and wherein the pallet lever is left free to be moved in one direction by a brushing contact with the pin and in the opposite way 75 through the tone arm lever extension and the make and break pivot.

6. In stopping means in talking machines, 80 a pallet lever, a pallet wheel, a pin thereon and another pin depending therefrom slightly in advance of the top pin, a tone arm mounting, a pivoted lever and an extension thereon operated from said mounting, a flat spring secured to the pallet lever, a make and break pivot on the spring adapted 85 to contact with said lever extension, a rocking lever adapted to bear at one end on the inner side of the spring and at the other to be rocked by the depending pin on the pallet 90 wheel as same rotates.

7. In stopping means in talking machines, 95 a pallet lever, a pallet wheel, a motor on a spindle that drives said pallet wheel, a plate pivotally disposed on said spindle and mounting said wheel, an upstanding pin on the wheel, a rocking lever on the end of the pallet lever, an inclining pallet and a tooth on the forward end of the rocking lever, means whereby the pin shall engage the tooth only when the movement of the tone 100 arm ceases, a pawl on the plate, a toothed quadrant in which the pawl may engage and braking means retained on the quadrant and which are released when the quadrant is 105 moved by the pawl.

8. In stopping means in talking machines, 110 a pallet lever, a pallet wheel, a motor driven spindle, a plate mounting said wheel pivotally disposed on said spindle, an upstanding pin on the pallet wheel, a rocking lever on the end of the pallet lever and an inclining pallet and a tooth on the end of the rocking lever, a tone arm mounting, a Z shaped pivoted lever having a curved base thereon actuated from the said tone arm mounting, a 115 knurled edge on said base, a flat spring secured to the pallet lever, a knife edge thereon adapted to contact with the lever extension, a rocking lever extending under the pallet wheel and the pallet lever, one end 120 of which bears against the inner side of the flat spring, a pawl on the plate, a toothed quadrant in which the pawl may engage and braking means retained on the quadrant and which are released when the quadrant is 125 moved by the pawl.

9. In a stopping means in a talking machine having a tone arm mounting and a Z shaped pivoted lever actuated from said mounting, a bracket on the mounting and 130

means for operating said lever from said mounting that consists of a post on the bracket, a jaw to the lever that is wider than the diameter of the post, a stop on the machine base plate and means for holding the lever against the stop until the post enters the jaw.

10. In stopping means in talking machines, a pallet lever, a pallet wheel, a motor on a spindle that drives said pallet wheel, an upstanding pin on the wheel, a rocking lever on the end of the pallet lever, an inclining pallet and a tooth on the forward end of the rocking lever, a tension spring that re-

tains the pallet lever in its normal position, 15 a tone arm mounting, a post thereon, a Z shaped pivoted plate actuated from said mounting, a curved extension or base to the Z plate, an inclined edge thereto near its outer end and a lever straddling the pallet lever spindle attached at one end to the tension spring which lever as it contacts with the inclined plane on the curved extension frees the pallet lever from the spring as the Z shaped lever is moved by the post. 20 25

In testimony whereof I affix my signature.

ERIC NEWHAM WATERWORTH.
